UNITED STATES PATENT OFFICE.

OLIVER D. H. BENTLEY, OF ROSLINDALE, MASSACHUSETTS, ASSIGNOR TO B. F. STURTEVANT COMPANY, OF BOSTON, MASSACHUSETTS, A CORPORATION OF MASSACHUSETTS.

GOVERNOR.

Application filed July 10, 1918. Serial No. 244,160.

To all whom it may concern:

Be it known that I, OLIVER D. H. BENTLEY, a citizen of the United States, residing at Roslindale, in the county of Suffolk and 5 State of Massachusetts, have invented certain new and useful Improvements in Governors; and I do hereby declare the following to be a full, clear, and exact description of the invention, such as will enable others 10 skilled in the art to which it appertains to make and use the same.

The present invention relates to governors for regulating the speed of prime movers and is more particularly designed for use 15 on steam engines.

The sensitiveness and efficiency of governors has heretofore been limited, to a considerable extent, because of the necessary employment of a steam-tight bearing or stuffing-box between the governor and the steam valve, through which the valve stem or spindle, actuated by the governor, must pass to enter the valve. This valve spindle moves 20 longitudinally through the bearing or stuffing-box, under the influence of the governor, to control the flow of steam through the valve. The resulting friction retards the movements of the valve spindle and lessens the sensitiveness of the governor. A stuffing-box or other steam-tight bearing is necessary, of course, to prevent the leakage 25 of steam from the valve, and particularly in high speed engines, where the steam pressure is very high and the stuffing-box must be tightly packed, the resistance to the movements of the valve spindle is a serious difficulty.

The general efficiency of governors as heretofore constructed has also been lessened 30 by friction and lost motion resulting from the employment of a series of links, levers or other connections between the centrifugal members and the valve spindle while constant attention has been required to keep 35 such connections continually lubricated.

One of the objects of the present invention is to eliminate, so far as possible, the frictional resistance of the valve spindle to longitudinal movement and thus to render the 40 governor more sensitive to slight changes of speed. To this end, one feature of the invention contemplates the imparting of rotary movement to the valve spindle, thereby greatly reducing the frictional resistance in

the bearing to the longitudinal movement of 55 the spindle and rendering the governor extremely sensitive.

A further object of the invention is to overcome the difficulties arising from the use of links, levers, and other connections, 60 and accordingly another feature of the invention contemplates the provision, in a governor, of centrifugal members mounted to act directly on the valve stem or spindle to impart longitudinal movement thereto. 65

Other features consist in the forming of the valve body as an integral part of the governor casing, and in certain other combinations and arrangements of parts tending to improve and simplify the construction of 70 governors and render them better adapted to operate at high speed.

The drawing shows in longitudinal sectional view a governor embodying what is now considered to be a preferred form of 75 the invention. A portion of the rotor shaft of a turbine engine is indicated at S, journaled in a ball bearing B supported by the side plate P of the engine casing. Threaded on to the outer end of the rotor shaft and 80 held fast thereon by set screws is the governor frame 3 which carries the several parts of the governor mechanism. Centrifugal members 4, of which there may be two or more within the governor frame, are spaced 85 outwardly about a central valve spindle 5, and are maintained in operative engagement with a head 6 fixed to the inner end of said valve spindle. The valve spindle is co-axial with the rotor shaft and is slidably 90 mounted in the hub 7 projecting inwardly from the adjustable sleeve 8 mounted in the outer end of the governor frame, and rotating therewith. The outer end of the valve 95 spindle 5 extends through a stuffing box 9 into steam chambers 10 and 11 formed in the housing 12 which encloses the governor mechanism, and is secured by bolts 13 to the plate P. The chamber 10 which receives steam from the boiler is partially surrounded by the chamber 11 from which steam is delivered to the engine but is separated therefrom by a web 14 integral with the casing 12. Communication between 100 chambers 10 and 11 is had through two diametrically opposed passages 15 and 16 in the web 14, said passages being in alignment with the valve spindle 5, which is adapted

105

to cooperate with the said passages to regulate the flow of steam from the chamber 10 through said passages 15 and 16 into the chamber 11 and thence to the engine. The valve spindle 5 is of slightly less diameter than the passages 15 and 16 so as to provide a loose sliding fit. The spindle, adjacent its end, is of reduced diameter, thus providing a balanced valve construction and rendering the mechanism more sensitive. Leakage from the steam chamber 16 along the valve spindle 5 is prevented by the stuffing box 9 comprising the packing 17 compressed by the follower 18.

15 A spring 19 surrounds the hub 7 of the adjustable sleeve 8 carried by the governor frame and is interposed between the bottom of a recess 20 in the sleeve 8 and the head 6, on the valve spindle, and acts upon said valve spindle head to move the valve spindle so as to increase the supply of steam to the engine, resisting the action of the centrifugal members which act to move the valve spindle in the opposite direction to diminish 25 the supply of steam. The centrifugal members 4 are in the shape of bell crank levers having knife edges 21 fulcrumed on the interior of the governor frame.

20 The longer arms 22 of the centrifugal members correspond to the weights in the usual form of governor and the shorter curved arms 23, which project inwardly to engage the valve spindle, have rounded ends 24 which roll smoothly over the surface 25 of the head as the centrifugal members swing about their fulcrums.

30 The sleeve 8 is screw-threaded into the open end of the governor frame and is provided with a head 26 adapted to be engaged by a wrench for the purpose of adjusting the sleeve. By means of such adjustment the compression of spring 19 may be varied to maintain the speed of the governor at the desired number of revolutions per minute.

45 It will be observed that the head 6 fixed on the inner end of the valve spindle 5 rotates with the governor frame, being held between the rotating centrifugal members 4 on one side and the spring 19 mounted in the rotating sleeve 8 on the other. Rotation is thus imparted to the valve spindle 5 which is thereby rendered extremely sensitive, moving freely longitudinally through the stuffing box upon the slightest variation in speed, notwithstanding the tight fit of the packing around the spindle. Owing to the absence of all links and levers between the centrifugal members and the valve stem, opportunity for wear and lost motion is avoided 50 and the permanent sensitiveness of the device is assured.

60 It is preferred to provide felt packing rings on both sides of the bearing B as follows: a ring 27 to engage the rotor shaft on the inner side of the plate P and another

ring 28 to engage the hub of the governor head so as to prevent leakage of oil or grease from the bearing, or the entrance of dust.

65 The parts of the governor herein described are compactly arranged within a housing which serves to protect them from injury and which contains also the valve body as an integral part thereof. The device is of simple and durable construction, is free from liability to get out of order, and 70 may be cheaply manufactured.

75 While I have herein disclosed but one embodiment of my invention and applied it to a single type of engine, it is to be understood that such is not the only embodiment 80 of which the invention is capable, nor is the invention necessarily limited in its application to engines utilizing steam as a motive fluid.

Having thus described my invention, what 85 is claimed is:

1. In a governor, the combination with a driven shaft and a support in which the shaft is journaled, of a throttling valve mounted on the support and through which a fluid flows continuously, a valve spindle mounted for longitudinal movement to vary the flow of fluid through the valve, and speed-controlled mechanism connecting the shaft and the spindle for actuating the valve 95 spindle longitudinally and for continuously rotating the spindle to reduce the frictional resistance to longitudinal movement, such rotational movement being without effect upon the flow of the fluid through the valve. 100

2. In a governor, the combination with a driven shaft and a support in which the shaft is journaled, of a housing secured to the support, a throttling valve carried at the outer end of the housing, a valve spindle mounted for longitudinal sliding movement, a stuffing box through which the spindle passes, and speed controlled mechanism located within the housing having positive connection with the shaft and frictional connection with the spindle for imparting longitudinal movement to the valve spindle, and for continuously rotating the valve spindle to reduce the frictional resistance of the stuffing box to longitudinal movement of 110 the spindle therethrough. 115

3. In a governor, the combination with a driven shaft and a support in which the shaft is journaled, of a housing secured to the support, a throttling valve carried at the outer end of the housing and having loosely fitting steam controlling members, a valve spindle mounted for rotary and longitudinal sliding movements within the housing and carrying one of the valve members, a stuffing box through which the valve spindle extends, and speed-controlled mechanism enclosed within the housing and connecting the shaft and spindle for imparting longitudinal sliding movement to the 120 125 130

valve spindle to control the flow of a fluid through the valve and for rotating the valve spindle to reduce frictional resistance to its longitudinal movement through the stuffing box.

4. In a governor, the combination with a driven shaft and a support in which the shaft is journaled, of a housing secured to the support having a valve chamber at its outer end, a valve, a valve spindle entering the valve chamber for controlling the flow of the fluid through the valve, and speed-controlled mechanism enclosed within the housing for actuating the valve spindle, the housing being removable without disturbing the speed-controlled mechanism and its connections.

5. In a governor mechanism, the combination of a spindle and a balanced valve carried thereby, a valve chamber, a steam tight bearing for the spindle in the wall of the valve chamber, a driven shaft in alignment with the spindle, and speed controlled mechanism mounted upon the shaft and located between the shaft and the valve chamber for rotating the spindle continuously to reduce the frictional resistance of the bearing and for moving it longitudinally to vary the position of the valve.

6. In a governor mechanism the combination of a rotating shaft, a stationary frame having bearings for said shaft, a frame secured on the end of said shaft and rotating

therewith, centrifugally operated members pivoted on said frame, a stationary housing secured to said first frame and surrounding said centrifugal members, said housing having a passage in line with said shaft, a valve member rotating coaxially with said shaft and adapted to be moved axially of the shaft by said centrifugal members to regulate the flow of fluid through said passage, and a coiled spring coaxially arranged with said shaft and opposing the action of said centrifugal members.

7. In a governor, the combination with a driven shaft of a balanced throttling valve mounted in axial alignment with the shaft, a spindle integral with the valve and mounted for longitudinal movement therewith, and speed controlled mechanism carried by the shaft and acting directly on the spindle for rotating the spindle and valve and moving the same longitudinally.

8. In a governor, the combination with a casing and a driven shaft having its end projecting through the casing, of speed controlled mechanism mounted upon the end of the shaft including a spindle and balanced valve mounted in alignment with the shaft, and a housing mounted at one end upon the casing and enclosing the speed controlled mechanism and carrying at its outer end a valve chamber for the balanced valve.

OLIVER D. H. BENTLEY.
